UNITED STATES PATENT OFFICE

HOWARD J. MURPHY, OF READING, MASSACHUSETTS, ASSIGNOR, BY MESNE ASSIGNMENTS, TO ALEMITE CORPORATION, OF CHICAGO, ILLINOIS, A CORPORATION OF DELAWARE

LUBRICATING APPARATUS

Application filed March 14, 1922. Serial No. 543,652.

This invention pertains to improvements in lubricating apparatus. It is among the objects of the invention to improve that form of lubricating apparatus wherein a lubricant-receiving element is adapted to be readily connected to and disconnected from a source of lubricant under pressure.

In the drawings, which show a preferred form of one embodiment of my invention:—
10 Figure 1 is a side elevation of a preferred form of lubricant-expelling device coupled to a lubricant-receiving element;

15 Fig. 2 is a longitudinal central section through the discharge end of the lubricant-expelling device illustrated in Fig. 1, showing the lubricant-receiving element in elevation;

20 Fig. 3 is a section on the same line as Fig. 2, being partly in elevation to show the relative position of various interior parts pursuant to coupling and valve opening operation;

25 Fig. 4 is a view similar to Fig. 3, but showing the relative position of the parts prior to the coupling operation;

Fig. 5 includes an end and a side elevation of a preferred form of coupling sleeve shown as retractile;

30 Fig. 6 includes a side and an end elevation of a preferred form of connecting sleeve;

Fig. 7 includes an end and a side elevation of a preferred form of sealing part;

Fig. 8 shows a valve packing washer; and

35 Fig. 9 includes a side and an end elevation of a preferred form of valve plunger.

Referring to the drawings and to the preferred form of my invention selected for illustrative purposes, I have shown a lubricant-expelling device resembling more or less the usual lubricant gun, having a barrel 10, a rear head 11 and a threaded stem 12 engaging threads on the head 11 and carrying the usual lubricant-expelling piston in the barrel 10. At the discharge end of the lubricant-expelling device, I have shown a coupling and valve mechanism for engagement with a lubricant-receiving nipple 14 having lateral projections 15 and presenting at one end thereof a lubricant-receiving aperture closed by the usual check valve 16. This nipple is, of course, as in the case of my co-pending applications filed herewith, intended to be secured to a part to be lubricated, as by threads 17, so that the nipple is held against rotation during the coupling and uncoupling operations.

The preferred form of coupling illustrated is carried by the front head 18 of the barrel 10 and includes a retractile sleeve 19 presenting an end opening 20 adapted to receive the projections 15 on the nipple 14 and presenting flanges 21 adapted to underlie the projections 15 when the sleeve or nozzle 19 is turned relative to the nipple. Cooperating with the retractile coupling sleeve 19, I have shown a sealing part 22 apertured to permit passage of lubricant therethrough to the lubricant-receiving opening in the nipple and carrying a more or less compressible sealing washer 23. In the preferred form of my invention illustrated, the sealing part 22 is held against rotation or turning movement relative to the nipple 14 when the nipple is carried in the nozzle by a connecting sleeve 24 having an aperture therethrough shaped to engage laterally the projections on the nipple 14 and to engage the square end 25 of the sealing part 22. The connecting sleeve 24 is held in its foremost position against the inside of the flange 21 by any suitable means typified by the spring ring 26 (Fig. 2), and the connection between the connecting ring 24 and the squared end 25 of the sealing part 22 is such as to permit sliding movement of the connecting sleeve relative to the sealing part. The connection between the coupling sleeve or nozzle 19 and its carrying parts connected to the head 18 is such that upon rotation of its carrying parts, the nozzle or coupling sleeve 19 will be retracted relative to the head of the gun, thus rendering unnecessary the movement of the sealing part 22 relative to the head of the gun during the coupling and uncoupling operations. Where, as in the preferred form of my invention illustrated, a valve is used which shuts off the opportunity for escape of lubricant from the lubricant-expelling device prior to uncoupling movement, any retractile movement of the sealing part 22 during uncoupling must be against

the pressure of the lubricant in the device, while, where the coupling sleeve is retracted, no such movement of the sealing part during either the coupling or uncoupling movement 5 is necessary. I have, therefore, mounted the sealing part 22 so that during the coupling and uncoupling movements it does not move in such a way as to have to operate in either direction against pressure of the lubricant. 10 Relative movement between the sleeve 19 and the sealing part 22 is effected by pin and slot means typified by the screw 40 carried by the sealing part 22 and having its head fitting a slot 41 in the retractile sleeve 19. Assuming 15 the nipple 14 to be held against rotation by the part to be lubricated, the sealing part 22 will be held against rotation by the connecting sleeve 24 engaging the side faces of the projections 15 on the nipple and engaging the squared end 25 of the sealing part. Therefore, when the barrel 10 of the gun is turned, the coupling sleeve 19 will be turned to bring the projections on the nipple from the position illustrated in Fig. 4 to the position illustrated in Fig. 2, in which these projections 25 overhang the flange portions 21, and at the same time the pin 40, cooperating with the slot 41, will retract the sleeve 19 as the screw 40 moves from the end of its slot at the top 30 of Fig. 3 to the end of said slot toward the bottom of Fig. 3.

The retractile coupling part 19 is of great advantage, whether associated with the type of valve illustrated or not, but I have provided therewith a particularly effective and desirable form of valve mechanism of the deferred action type so that the valve opening operation does not begin until the coupling operation is completed and so that 40 the uncoupling operation does not commence until the valve closing operation is completed, thus preventing leakage of lubricant arising from pressure in the grease expelling device during or pursuant to coupling and uncoupling operations.

The preferred form of valve illustrated is operated by movement of the barrel 10 toward the nipple 14 pursuant to coupling operation and by movement thereof away from 50 said nipple preparatory to the uncoupling operation. I have effected this valve-operating movement by providing inclined means typified by the slot 50 in the coupling sleeve 19 cooperating with the pin provided by 55 the screw 51 fixed relative to the head 18 of the barrel 10. This slot 50 is preferably provided with a relatively abrupt portion 53 which opposes movement of the head relative to the coupling sleeve during the coupling 60 operation, but which permits such movement pursuant to the coupling operation. Thus, prior to coupling, the pin 51 is in the position illustrated in Fig. 4. At the end of the coupling operation, the retractile sleeve 65 19 will have been drawn back sufficiently so

that the pin will be out of the abrupt end 53 of the slot and, pursuant to turning of the head of the barrel without corresponding turning of the coupling sleeve 19, the pin will move along the slot 50 to the position illustrated in Fig. 3, thus pulling the head of the gun forwardly. This forward movement of the head relative to the sealing part 22 opens a valve which may be provided by a valve stem 60 threaded into the sealing part 22 and suitably apertured to permit passage of lubricant therethrough while open and to oppose passage of lubricant therethrough when closed. To this end, I have provided a valve seat 61 carried by the head 18 of the gun, against which the head 62 carried by the valve stem 60 may seat with the lubricant passage 63 below the valve seat and removed from the lubricant in the gun when closed, while exposed thereto when open.

The operation of the preferred form of apparatus illustrated is as follows. Assuming the nipple to be separated from the gun and to be carried by a part to be lubricated, the gun may be grasped by the rear end thereof or even by the handle on the stem 12, and the nozzle end of the gun slipped over the head of the lubricant-receiving nipple to the position viewed in Fig. 4. The valve is now closed and the pin 40 at the extreme top of the slot 41, while the valve-operating pin 51 is in the abrupt portion 53 of the slot 50. The projections on the nipple 19 fit the interior of the connecting sleeve 24, and the connecting sleeve 24 engages the squared end 25 of the sealing part 22 so that there can be no rotation either of the nipple, held by the part to be lubricated, or of the connecting sleeve 24 or of the sealing part 22. If now the barrel of the gun be turned to the right, which may ordinarily be effected, if desired, by turning the handle attached to the screw-threaded stem 12, there will be no rotation between the head 18 or parts directly connected therewith and the coupling sleeve or nozzle 19 to open the valve because the valve-operating pin 51 is in the steep portion 53 of the slot 50. Therefore, the coupling sleeve 19 will turn with the barrel of the gun and the coupling pin 40 will ride down the sleeve 41, retracting the coupling sleeve 19 from the position illustrated in Fig. 4 to the position illustrated in Fig. 2, this retraction being accompanied by relative turning movement which brings the projections 15 on the nipple over the flanges 21 of the coupling sleeve. When retraction has occurred sufficiently to press the head of the nipple firmly against the sealing washer 23, back-supported by the sealing part 22, a tight joint will be effected and, because of the retraction of the coupling sleeve, the pin 51 will be out of the steep portion 53 of the slot 50 and, on

further turning of the barrel, the pin 51 may ride down the inclined slot 50 to the position illustrated in Fig. 3, thus drawing the entire barrel and its head 18 forwardly 5 relative to the nipple 14 and relative to the coupling sleeve 19 in the sealing part 22. The valve stem 60 carrying the valve head 62 will remain stationary with the sealing part 22 and, as the head 18 moves forward, 10 the seat 61 will move with it away from the head 62 on the valve stem, thus opening the ports 63 and permitting passage of the lubricant from the interior of the lubricant-expelling device through the valve and through 15 the sealing part and disc to the lubricant-receiving nipple. I preferably provide resilient means typified by the spring 70 (Fig. 2) normally tending to hold the sealing part 22, and therefore the valve stem 60 and parts 20 carried thereby, in forward position relative to the head 18. In the form of my invention illustrated, this spring is interposed directly between the sealing part 22 and the head 18, which, as illustrated, is integral with parts 25 cooperating in the coupling and valve-operating movements.

While I have shown and described a preferred form of one embodiment of my invention, it will be understood that changes 30 involving omission, substitution, alteration and reversal of parts, and even changes in the mode of operation, may be made without departing from the scope of my invention, which is best defined in the following 35 claims.

Claims:

1. Lubricating apparatus comprising a lubricant-expelling gun having a member rigid therewith, a coupling carried by said member and presenting relatively movable parts 40 movable toward each other for gripping between them a portion of a lubricant-receiving nipple to provide a tight joint, a valve, and means for causing relative movement between said parts and said gun to open said valve.

2. Lubricating apparatus comprising a lubricant-expelling gun, said gun having a rigid extension for supporting a coupling, 50 said coupling presenting relatively movable parts movable toward each other during coupling operation for gripping between them a portion of a lubricant-receiving nipple to provide a tight joint, a longitudinally movable valve, and means for causing relative movement between said parts and said gun to open said valve.

3. Lubricating apparatus comprising a lubricant-expelling gun having a rigid extension, a coupling carried by said extension and presenting relatively movable parts movable 60 toward each other during coupling operation for positively gripping between them a portion of a lubricant-receiving nipple to provide a tight joint, a longitudinally movable

valve, and means for causing relative movement between said parts and said gun to open said valve, including a valve part carried by and movable with one of said movable parts.

4. A lubricant-expelling gun having rigidly guided with respect thereto two relatively movable coupling parts adjacent its discharge end, and a valve, said parts and said gun movable relative to each other to open said valve. 70

5. A lubricant-expelling device having two relatively movable coupling parts adjacent its discharge end, a valve, said parts movable together relative to said device to open said valve, and a spring urging both of 80 said parts away from said device.

6. A lubricant gun carrying at the discharge end of its barrel a valved coupling comprising an element longitudinally movable by rotation thereof relative to a cooperating non-rotatable part and a valve axially operable by rotation of means rotatable relative to a cooperating non-rotatable part and a valve axially operable by rotation of means rotatable relative to said element and said 90 part. 85

7. Lubricating apparatus comprising a lubricant gun presenting at its discharge end a coupling for connecting a source of lubricant under pressure to a lubricant-receiving part, 95 said coupling including a sealing part and a retractile part for pressing the lubricant-receiving part against said sealing part to provide a tight joint therebetween, a valve part, and oppositely inclined cam means for causing relative movement of said parts. 100

8. Lubricating apparatus comprising a lubricant gun presenting at its discharge end a coupling for engaging a source of lubricant under pressure to a lubricant-receiving part, 105 said coupling including a sealing part and an inclined plane-operated retractile part for pressing the lubricant-receiving part against said sealing part to provide a tight joint therebetween during coupling operation, a 110 valve, and an oppositely inclined plane-operated part for opening said valve.

9. Lubricating apparatus comprising a lubricant gun presenting at its discharge end a coupling for engaging a source of lubricant 115 under pressure to a lubricant-receiving part, said coupling including a sealing part and a pin and inclined slot-operated retractile part for pressing the lubricant-receiving part against said sealing part to provide a tight 120 joint therebetween, a valve and separate and distinct inclined plane-operated means for operating said valve after operation of said sealing part by said first mentioned pin and slot means. 125

10. Lubricating apparatus comprising a lubricant gun presenting at its discharge end a coupling for engaging a source of lubricant under pressure to a lubricant-receiving part, 130 said coupling including a sealing part and a

retractile part for pressing the lubricant-receiving part against said sealing part to provide a tight joint therebetween, and interengaging means holding said sealing part 5 against rotation relative to the lubricant-receiving part during the coupling operation.

11. Lubricating apparatus comprising a lubricant gun presenting at its discharge end a coupling for engaging a source of lubricant under pressure to a lubricant-receiving part, said coupling including a sealing part and a retractile part for pressing the lubricant-receiving part against said sealing part to provide a tight joint therebetween, and a sleeve 10 presenting a non-circular aperture therethrough for holding said sealing part against rotation relative to the lubricant-receiving part during the coupling operation.

12. Lubricating apparatus comprising, a 20 lubricant-expelling gun for connection to a lubricant-receiving nipple, said gun carrying a coupling presenting a sleeve retractile toward said gun during the coupling operation, a sealing part, and means preventing rotation of said sealing part with respect to said nipple during the coupling operation.

13. Lubricating apparatus comprising, a 30 lubricant-expelling gun for connection to a lubricant-receiving nipple, said gun directly carrying a coupling presenting a sleeve retractile toward said gun during the coupling operation and a valve openable subsequent to the coupling operation.

14. Lubricating apparatus comprising, a 35 lubricant-expelling gun for connection to a lubricant-receiving nipple, said gun directly carrying a coupling presenting a sleeve retractile toward said gun during the coupling operation and a longitudinally movable valve openable subsequent to the coupling operation.

15. Lubricating apparatus comprising, a 45 lubricant-expelling gun for connection to a lubricant-receiving nipple, said gun carrying a coupling presenting a sleeve retractile toward said gun during the coupling operation by rotation of said gun, a valve openable by rotation of said gun in coupling direction and 50 detent means deferring valve opening operation until after the coupling operation.

16. A lubricant-expelling gun having a coupling at the discharge thereof presenting a retractile sleeve, a sealing part and a second sleeve within said retractile sleeve permitting 55 turning of the latter thereon and opposing rotation of said sealing part with said retractile sleeve during the coupling and uncoupling operations.

17. A lubricant-expelling gun having a 60 coupling at the discharge thereof presenting a retractile sleeve, a sealing part and a second sleeve within said retractile sleeve and longitudinally movable therewith permitting turning of the latter thereon and opposing rotation of said sealing part with said retractile 65

sleeve during the coupling and uncoupling operations.

18. A lubricant-expelling gun having a coupling at the discharge thereof presenting a retractile sleeve, a sealing part and a second sleeve within said retractile sleeve and longitudinally movable therewith permitting turning of the latter thereon and opposing rotation of said sealing part with said retractile sleeve during the coupling and uncoupling 70 operations, said second sleeve longitudinally slidable relative to said sealing part.

19. A lubricant gun provided adjacent its discharge end with a valved coupling comprising an element longitudinally movable 80 by rotation thereof relative to a cooperating non-rotatable part and a valve axially operable by rotation of means rotatable relative to said element and said part, the means for operating said valve including cooperating pin and inclined slot means operatively interposed between said element and the body of the gun.

20. Lubricating apparatus comprising, a source of lubricant under pressure presenting 90 a coupling having a torque-pressed sealing element non-rotatable relative to a lubricant-receiving nipple, valve means, and co-ordinated detent means controlling operation of said valve means and said coupling while permitting operation of said torque-pressed sealing element at all times when under torque in sealing direction.

21. In a nozzle for lubricators, the combination of a body, a member slidably mounted 100 in the body, means for moving the body to cause a part to be lubricated to be engaged by said member for making a sealed joint between said part and said member, a valve seated in the body, means for forcing the member forwardly and holding the valve against its seat, and means whereby said body is permitted to move while said member is in sealed engagement with said part before said valve will be moved from its seat, substantially 105 as described.

In testimony whereof, I have signed my name to this specification.

HOWARD J. MURPHY.

CERTIFICATE OF CORRECTION.

Patent No. 1,847,357.

Granted March 1, 1932, to

HOWARD J. MURPHY.

It is hereby certified that error appears in the printed specification of the above numbered patent requiring correction as follows: Page 3, lines 88 to 90, claim 6, strike out the words "to a cooperating non-rotatable part and a valve axially operable by rotation of means rotatable relative"; and that the said Letters Patent should be read with this correction therein that the same may conform to the record of the case in the Patent Office.

Signed and sealed this 26th day of April, A. D. 1932.

(Seal)

**M. J. Moore,
Acting Commissioner of Patents.**
